UNITED STATES PATENT OFFICE.

JOHN F. COURSON, OF PITCAIRN, PENNSYLVANIA.

DRAFT-GEAR.

1,256,297.

Specification of Letters Patent. Patented Feb. 12, 1918.

Application filed April 21, 1917. Serial No. 163,599.

To all whom it may concern:

Be it known that I, JOHN F. COURSON, citizen of the United States, residing at 424 Third street, Pitcairn, in the county of Allegheny and State of Pennsylvania, have invented certain new and useful Improvements in Draft-Gears, of which the following is a specification.

My invention consists of an improvement 10 in draft gears of the general class utilizing springs and friction shoes, in connection with centrally arranged expanding wedge mechanism operable upon buffing or pulling, to effect resistance to such strains through 15 the mechanism inclosed within an embracing cylinder or casing.

The particular objects in view are to provide, in a gear of this type, having a series 20 of friction shoes within the casing and adapted to frictionally engage the inner face thereof, wedging means for exerting a distending or expanding movement to the friction shoes throughout their length and simultaneously operable as to the front and 25 rear portions of the friction shoes, whereby to produce an equal pressure upon such portions of the shoes during buffing or pulling strains, and in proportion to the said strains.

30 These objects are secured by providing a central wedge member having at each end series of wedge faces, oppositely disposed as to each series, and operable in connection with the shoes at one end, and co-acting associated elements at the other end, to impart 35 the desired movement to the friction shoes and with a resulting desired frictional engagement therewith, as hereinafter described.

40 The invention is illustrated, in certain preferred forms in the accompanying drawings in which:

Figure 1 is a longitudinal vertical sectional view through the complete gear as 45 assembled, the parts being shown in normal extended position, as indicated by the section line 1, 1 of Fig. 2;

Fig. 2 is a cross sectional view indicated by the line II, II, of Fig. 1;

50 Fig. 3 is a longitudinal sectional view similar to Fig. 1 showing the gear compressed, as in buffing;

Fig. 4 is a perspective detail view of the follower;

55 Fig. 5 is a similar view of one of the intermediate wedge blocks;

Fig. 6 is a similar view of one of the friction shoes;

Fig. 7 is a similar view of the double ended central wedge; 60

Fig. 8 is a sectional detail view showing a modified construction as to the follower and intermediate wedge blocks;

Figs. 9 and 10 are detail sectional views showing further modifications embodying 65 lever mechanism between the follower and the intermediate wedge blocks;

Fig. 11 is a perspective detail view of one 70 of the intermediate wedge blocks as used in Fig. 10;

Figs. 12 and 13 are sectional detail views, similar to the construction shown in Fig. 1, but showing the use of a rolling member between the wedging faces.

In the drawings, 2 represents the drawbar 75 of the coupler, connected with the front end portions of side bars 3 by a transverse bolt or key 4 which extends through slots 5 in the front portions thereof and through the drawbar, connecting the parts, and retained 80 in position by cotter pins 6 or the like at each end. Bars 3 are connected with casing 7 of the gear by their rear portions which engage lugs 8 thereof, and casing 7 bears by its rear end backwardly against a rear 85 follower 9, mounted between the center sills 10, 10. A lower supporting plate 11, or other suitable means extending across underneath the casing from one center sill to the other, supports the casing in operative 90 position.

Arranged within the front cylindrical portion of the casing are the segmental friction shoes 12, conforming to the curvature of the casing. Each shoe, of which there 95 may be four, or any other suitable number, is rounded along its inner face portion, or otherwise suitably shaped as indicated at 13, whereby to present at each end portion a confronting wedging face.

The central wedge, as shown in Fig. 7, is 100 of a single integral piece having a middle connecting bar or neck portion 14 and terminal wedge portions 15, 16. Each of said portions is in the form of a truncated pyramid with the wedge faces converging inwardly from each end portion, as shown.

The wedge faces of the rear portion 16 engage directly against the inner rounded faces 13 of the friction shoes and operate to 105 distend the shoes when the wedge moves forwardly. Similarly, the wedge faces of

the front portion 15 converge inwardly toward the rear, and in the principal construction illustrated, these faces are engaged by the confronting faces of intermediate 5 wedge blocks 17. Said blocks are provided with outer faces 18, which in turn engage the front inner faces 13 of the friction shoes, in a manner opposite to that of the wedge engagement with their rear portions. Faces 10 18 of the intermediate wedge blocks are, with respect to the longitudinal center of the gear, preferably somewhat more blunt or obtuse than the inner faces which engage wedge faces of portion 15, providing a differential angle engagement between the 15 front central wedge and the friction shoes.

Intermediate wedge blocks 17 abut, by their front bearing faces 19, against rearwardly projecting faces 20 of follower 21, 20 which is mounted between the rear end of the drawbar 2 and the front end of casing 7. While the faces 20, as shown, extend rearwardly from the main body portion of the follower, such construction is not essential 25 except in providing for sufficient clearance for the parts in closed position, as indicated in Fig. 3.

Interposed between the rear end of casing 7 and friction shoes 12 is a cushioning 30 spring 22, while an inner similar spring 23 is inserted between the rear end of the casing and the rear end of the compound central wedge, and engaging the rear face 23' thereof. These springs effect 35 sufficient pressure against the friction shoes and central wedge, respectively, in compressed position, to produce a considerable degree of resistance and resulting friction, and coöperate with the other parts in the 40 entire operation.

In action, under buffing strains, rearward movement of the drawbar 2 and follower 21 effects rearward movement of the differential angle intermediate wedge blocks 45 17, thrusting the friction shoes 12 inwardly of the casing. At the same time, by reason of the inner acute angle faces of blocks 17, they operate to force the central composite wedge in a forward direction, with relation 50 to the friction shoes 12, by engagement with the faces of the front wedge portion 15 thereof. The result of such action, in connection with the pressure exerted by spring 23, is to force the wedge faces of 55 the rear wedge 16 against the rear inner faces of the friction shoes thereby effecting the spreading of the shoes at their inner portions. By this means, the friction shoes are distended equally throughout their 60 length during their inward movement, resulting in a high degree of frictional engagement with the relatively stationary casing 7, and in proportion to the buffing strains.

65 Likewise, in pulling, forward movement

of the casing 7, by side bars 3, and in connection with the springs 22, 23, effects the same result, due to the resistance of the relatively stationary follower 21.

In each operation the intermediate wedge 70 blocks 17 operate to not only distend the front portions of the friction shoes 12, but to draw the central wedge toward the intermediate wedge blocks, thus effecting a corresponding pressure outwardly against the 75 rear portions of the friction shoes.

In Fig. 8 the construction and operation is substantially the same as just described, excepting that the rearwardly extended portion of the follower 20^a of follower 80 21^a is beveled or wedge faced, as indicated, and engages the correspondingly beveled wedge faces 19^a of the intermediate wedge blocks 17^a, operating to thrust them inwardly in buffing, or to provide wedging resistance 85 in pulling, with additional force. The other parts of the gear are the same as above described and similarly identified by numerals having the exponent "a".

In Fig. 9 I show a further modified construction in which the central wedge is provided with a rear wedge portion 16^b only, and a forwardly extending shank 14^b adapted to provide a fulcrum bearing for lever members 24. These members, as 90 shown, are provided with inner rounded bearing portions which seat in suitable receiving sockets 25 of shank 14^b, and bear by their outwardly and forwardly curved terminals 26 in receiving sockets 27 in the 100 projecting portion 20^b of follower 21^b. Interposed between the lever members 24 and the front portions of friction shoes 12^b is an intermediate wedge block 17^b, substantially square in outline, embracing the bar 14^b as 105 indicated by the dotted lines. The inner wedge faces 18^b of block 17^b engage against the front inner portions of the friction shoes, while the front flat face of the intermediate wedge bears against the rear 110 rounded face of the lever members 24, between their inner fulcrum bearing portions and their outer terminals. In action, the strains, either in buffing or pulling, effect relatively opposite movement of the wedge 115 16^b and wedge 17^b, giving the desired lateral movement to the friction shoes with the resulting desired friction.

In Fig. 10 the construction and operation is generally the same as just described, the 120 central wedge having a tapering shank portion 14^c while the intermediate wedges 17^c are individually like wedges 17, but so designed as to be incorporated with the other parts in snugly fitting position, 125 whereby to permit individual lateral movement with the resulting effect, as to the central wedge and the friction shoes, in distending them. The several other parts of the construction of Fig. 10 are substan- 130

tially similar to that shown and described in Fig. 9, and similarly indicated by numerals having the exponent "c".

With either of the constructions above described, and as illustrated, the general effect is the same in producing a regular even movement to the friction shoes throughout the various degrees of movement of the parts with a proportioned 10 equal distribution of the power and a resulting evenly distributed frictional engagement. Due to the arrangement and design of the wedge faces, and their angles, the parts are readily and promptly released 15 upon cessation of the operating strains, resuming their normal position without binding and with practically no lost motion. A feature of advantage in having the shank 14° tapered, as shown in Fig. 13 is that any 20 lost motion due to wear or other causes is avoided or absorbed, the intermediate wedges 17° tending to always approach and seat against the faces of the friction shoes.

In Figs. 12 and 13 I show the mechanism 25 provided with rolling bearings between the confronting faces of the active wedge members, the construction otherwise being the same as already described. In Fig. 12 the parts are similarly numbered with the exponent "d" and between the shoe 12^d and block 17^d is interposed a roller 28 mounted for movement in a suitable recess between these parts.

In Figs. 13 a roller 28° is interposed between the front wedge 15° and the block 17° 35 for the same purpose, and, if desired, rollers may be used in both ways in the same gear. By this means, I provide easy rolling bearings, and these may, if desired, be used in 40 preference to the wedge faces.

The advantages of the invention will be readily understood and appreciated by all those familiar with this class of mechanism. It provides a construction which is simple 45 and compact, economical to manufacture, and capable of performing its desired functions in generating a high degree of frictional resistance within the prescribed limitations of gears of this class.

50 The gear may be changed or varied in detail construction or design, by the skilled mechanic, but all such changes are to be considered as within the scope of the following claims.

55 What I claim is:

1. In a friction draft gear, a casing, friction shoes engaging the casing having inner outwardly flaring wedging portions, a central wedge bar having a wedge member at 60 one end engaging the friction shoes, a relatively movable wedge member on the central wedge bar engaging the friction shoes, and means for actuating said parts to effect lateral movement to the friction shoes.

65 2. In a friction draft gear, a casing, fric-

tion shoes engaging the casing having inner outwardly flaring wedging portions, a central wedge bar having a wedge member at one end engaging the friction shoes, a relatively movable wedge member on the central 70 wedge bar engaging the friction shoes, and means for actuating said parts to effect lateral and longitudinal movement to the friction shoes.

3. In a friction draft gear, a casing, friction shoes engaging the casing having inner outwardly flaring oppositely disposed wedging portions, a central wedge bar having a wedge member at one end engaging the friction shoes, a relatively movable wedge member 75 on the other end of the central wedge bar engaging the friction shoes, a drawbar operatively connected with the casing, and means between the drawbar and the relatively movable wedge member for moving it 80 and effecting movement of the wedge bar in an opposite direction.

4. In a friction draft gear, a casing, friction shoes engaging the casing having inner outwardly flaring oppositely disposed wedging portions, a central wedge bar having a wedge member at one end engaging the friction shoes, a drawbar operatively connected with the casing, and means between the drawbar and the relatively movable wedge members for moving them and effecting movement of the wedge bar in an opposite direction. 90

5. In a friction draft gear, a casing, friction shoes engaging the casing having inner outwardly flaring oppositely disposed wedging portions, a central wedge bar having a wedge member at one end engaging the friction shoes, a series of relatively movable wedge members on the other end of the central wedge bar engaging the friction shoes, a drawbar operatively connected with the casing, and means between the drawbar and the relatively movable wedge members for moving them and effecting movement of the wedge bar in an opposite direction. 105

6. In combination, a casing, a relatively movable drawbar connected with the casing, friction shoes engaging the casing having inner outwardly flaring oppositely disposed friction faces, a central wedge bar having a wedge portion engaging the wedge 115 faces of the shoes at one end thereof, a series of relatively movable wedge members between the bar and the wedge faces of the shoes at the other end thereof, and means between the drawbar and the relatively movable wedge members for moving them and effecting movement of the wedge bar in an opposite direction. 120

7. In combination, a casing, a relatively movable drawbar connected with the casing, 130

- friction shoes engaging the casing having inner outwardly flaring oppositely disposed friction faces, a central wedge bar having at one end a wedge portion engaging the wedge faces of the shoes at one end thereof and having an oppositely disposed wedge portion at the other end, a series of relatively movable wedges between said oppositely disposed wedge portion of the bar and the wedge faces of the shoes at the other end thereof, and means between the drawbar and the relatively movable wedges for moving them and effecting movement of the wedge bar in an opposite direction.
15. 8. In combination, a casing, a relatively movable drawbar connected with the casing, friction shoes engaging the casing having inner outwardly flaring oppositely disposed friction faces, a central wedge bar having inwardly converging faces at each end engaging the friction shoes and relatively movable wedges respectively, relatively movable wedges between one set of wedge faces of the bar and the friction shoes, and means embodied with the drawbar for imparting movement to the relatively movable wedges.
9. In combination, a casing, a relatively movable drawbar connected with the casing, friction shoes engaging the casing having inner oppositely disposed friction faces, a central wedge bar having inwardly converging faces at each end engaging the friction shoes and relatively movable wedges respectively, relatively movable differential angle wedges between one set of wedge faces of the bar and the friction shoes, and means embodied with the drawbar for imparting movement to the relatively movable wedges.
40. 10. In combination, a casing, a relatively movable drawbar connected with the casing, friction shoes engaging the casing having inner outwardly flaring oppositely disposed friction faces, a central wedge bar having inwardly converging faces at each end engaging the friction shoes and relatively movable wedges respectively, relatively movable wedges between one set of wedge faces of the bar and the friction shoes, and a follower between the drawbar and said relatively movable wedges.
11. A friction gear having a casing, a series of laterally and longitudinally movable friction shoes therein, a central wedge having opposed sets of inwardly converging faces, one set of faces engaging the friction shoes at one end portion thereof, a drawbar connected with the casing, a follower between the drawbar and the casing, and mechanism actuated by the drawbar adapted to effect longitudinal movement of the central wedge and embodying separately movable wedges between a portion of the central wedge and the friction shoes.
12. A friction gear having a casing, a series of laterally and longitudinally movable friction shoes therein, a central wedge having at each end a series of inwardly converging wedge faces and engaging the friction shoes by one of said series, a drawbar connected with the casing, a follower between the drawbar and the casing, and a series of relatively movable wedges between the friction shoes and the other series of faces of the central wedge and engaging the follower.
13. A friction gear having a casing, a series of laterally and longitudinally movable friction shoes therein, a central wedge having at each end a series of inwardly converging wedge faces and engaging the friction shoes by one of said series, a drawbar connected with the casing, a follower between the drawbar and the casing, and a series of relatively movable differential angle wedges between the friction shoes and the other series of faces of the central wedge and engaging the follower.
14. A friction gear having a casing, a series of laterally and longitudinally movable friction shoes therein, a central wedge having at each end a series of inwardly converging wedge faces and engaging the friction shoes by one of said series, a drawbar connected with the casing, a follower between the drawbar and the casing having inner bearing projections, and a series of relatively movable wedges between the friction shoes and the other series of faces of the central wedge and engaging the projections of the follower.
15. A friction gear having a casing, a series of laterally and longitudinally movable friction shoes therein, a central wedge having at each end a series of inwardly converging wedge faces and engaging the friction shoes by one of said series, a drawbar connected with the casing, a follower between the drawbar and the casing having inner wedge faced-bearing projections, and a series of relatively movable wedges between the friction shoes and the other series of faces of the central wedge and engaging the wedge faced projections of the follower.
- In testimony whereof I hereunto affix my signature.
- JOHN F. COURSON.
